By E. G. Cromman, his Attorney.

UNITED STATES PATENT OFFICE.

ELMER L. SLOAN, OF JOPLIN, MISSOURI.

AUTOMATIC BURGLAR-PROOF SASH-LOCK.

1,077,312.

Specification of Letters Patent.

Patented Nov. 4, 1913.

Application filed January 21, 1913. Serial No. 743,372.

To all whom it may concern:

Be it known that I, ELMER L. SLOAN, a citizen of the United States of America, residing at Joplin, in the county of Jasper and State of Missouri, have invented certain new and useful Improvements in Automatic Burglar-Proof Sash-Locks, of which the following is a specification, reference being had therein to the accompanying drawing.

10 This invention relates to a sash lock and has special reference to a device of this character which is provided with means for automatically locking the same.

15 Another object of this invention is the production of an efficient means for holding the latching member in a locked position after the same engages the keeper.

20 A still further object of this invention is the production of a safety latch for holding the latching member in a position whereby the same may be automatically released for engaging the keeper.

25 With these and other objects in view this invention consists of certain novel combinations, constructions, and arrangements of parts as will be hereinafter fully described and claimed.

30 In the accompanying drawing:—Figure 1 is a perspective view of the lock illustrating how the same appears prior to the locking engagement. Fig. 2 is a top plan view of the device in a locked position. Fig. 3 is a side view of the latching member and the base. Fig. 4 is a longitudinal section 35 of the latching member showing the keeper in elevation. Fig. 5 is a bottom plan view of the base. Fig. 6 is a perspective view of the base. Fig. 7 is a perspective view of the keeper.

40 Referring to the accompanying drawing by numerals it will be seen that the device is used in combination with the ordinary sash members 1 and 2. The sash member 1 is provided with the keeper 3 which is formed to 45 constitute a retaining finger 4.

50 The sash 2 is adapted to carry the base and latching member. The base member comprises a rectangular body 5 which carries at its side portion the depending flanges 6. One of the depending flanges 6 is provided with a cut-away portion 7 and an entrance pocket 8. When the base is placed 55 upon the sash 2 it is positioned so as to allow the cut-away portion 7 and the entrance pocket 8 to be placed adjacent to the sash which carries the keeper 3. The en-

trance pocket 8 is so positioned so as to allow the keeper to pass therethrough when the window is closed. The base 5 is also provided with a pivot member which comprises the rounded head 9 in which is formed the groove 10. A coil spring 11 is positioned within this groove 10 and is fastened at the end 12 to the base whereby the head 9 is normally urged in one direction. Integrally carried by the head 9 is a squared neck 13 which is formed adjacent the rounded bearing portion 14. This rounded bearing portion 14 is adapted to work within the aperture 15 formed in the base 5, while the squared neck 13 is adapted to extend above the same. The latching member comprises a body 16 which is adapted to be engaged by the squared neck 13 whereby the same will be rotatably mounted upon the base. This body 16 is provided with an extended portion 17 which is provided with the integrally formed sleeve 18 adjacent which is formed the gripping portion 19.

Positioned within the sleeve 18 there is a locking arm 20 which terminates in the laterally extending neck 21 which extends to a position adjacent the gripping member 19. The opposite end of the locking arm 20 is provided with the depending finger 22 which is adapted to pass through the aperture 23 formed in the latching member 16 and into the opening 24 formed in the base 5. It will be seen that by use of this locking arm the latching member will be securely locked in position as illustrated in Figs. 2 and 4, whereby after the window has been closed it will be impossible to move the latch member from the outside of the window. When it is desired to move the latching member 16 the neck 21 is gripped and drawn toward the gripping portion 19 whereby the finger portion 22 will be withdrawn from engagement with the latching member 16 and the base whereby the latching member may be easily swung. It will of course be seen that the latching member 16 is provided with a notched portion 25 which is adapted to register with the receiving pocket 8 whereby the keeper 3 may easily pass therethrough.

In order to hold the latching member 16 in such a position as to allow the keeper to pass through the receiving pocket 8 and the notched portion 25 before the same is engaged by this latching member the up-standing flange 26 of the latching member 16 is provided with the laterally extending

lug 27. The base 5 is also provided with a bearing lug 28 and with the openings 29 and 29'. Carried by the base there is a safety latch which comprises an elongated body 30 which terminates at one end of the upwardly extending arm 31 and at the other end with the inclined portion 32. As illustrated in Fig. 1 it will be seen that when the window is open that the lug 27 will rest behind the upwardly extending arm 31 whereby the latch portion 25 will register with the receiving pocket 8. However, when the sash 2 is moved downwardly the inclined portion 32 will strike upon the sash 1 whereby the upwardly extending arm 31 will be swung outwardly and will in this manner release the lug 27 and will allow the latching member 16 to spring by means of the spring 11. By means of this safety latch it will be seen that the latching member will normally be held in such a position as to allow the keeper to pass in such a position as to allow the same to be engaged by this latching member for securely locking the same. If by some means the latching member 16 were moved around the lug 27 would strike upon the upstanding finger 31 whereby the rotary movement of this latching member 16 would be checked. Since this lug would strike upon the front side of this upstanding finger 31 the latch portion 25 would not register with the receiving pocket 8 but would overhang this receiving pocket 8 and would thereby prevent the two sashes from being moved relative to each other and would in this manner still hold the device in a locked position.

From the foregoing description it will be seen that a sash lock has been produced whereby the latch member may be swung so as to be placed in such a position as to allow the sashes to be moved relative to each other and which is also provided with means for holding the same in an operable position whereby when this means is removed the latching member will engage the keeper for holding the device in a locked position and that the latch member is also provided with a secondary locking member for securely holding the latching member against rotation upon the base.

Having thus described the invention what is claimed as new, is:—

1. A sash lock comprising a base, a latching member pivotally mounted upon said base, means for urging said latching member to swing in one direction, a safety latch car-

ried by said base comprising an elongated body, an upwardly extending arm carried by one end of said body, an inclined finger carried by the other end of said body, said upwardly extending arm adapted to engage said latching member for holding said latching member in a set position, said inclined finger adapted to be engaged by a window sash, whereby said inclined finger will swing upwardly and the upwardly extending arm will swing outwardly from engagement with said latching member for allowing said latching member to swing into engagement with a keeper.

2. A sash lock comprising a base, a latching member pivotally mounted upon said base, means for urging said latching member to swing in one direction, a safety latch comprising a body, said body positioned upon the under side of said base for protecting the same, said body having an upwardly bent finger, at one end extending through said base, said latching member provided with a lug, said arm adapted to engage said lug for holding said latching member in a set position, said body having an inclined finger at its opposite end, said inclined finger adapted to be swung upwardly for swinging said arm from engagement with said lug, whereby said latching member can swing into engagement with a keeper.

3. A sash lock comprising a base, a latching member pivotally mounted upon said base, said latching member provided with a neck, a sleeve integrally formed upon said neck, a locking arm positioned within said sleeve, said locking arm provided with a depending finger, said base and said latching member provided with registering apertures, said finger fitting in said apertures for holding said latching member against pivotal movement, and an upwardly extending neck carried by said locking arm, said neck positioned adjacent the outer end of said neck of said latching member, whereby said upwardly extending neck may be moved for lifting said finger from engagement with base and latching member for allowing said latching member to be swung.

In testimony whereof I hereunto affix my signature in presence of two witnesses.

ELMER L. SLOAN.
